A. T. CARNES

HOSE NOZZLE

Filed Nov. 1, 1927

Inventor.
Alvans T. Carnes
By Hustonson, Atty.

UNITED STATES PATENT OFFICE.

ALMUS T. CARNES, OF KANSAS CITY, MISSOURI.

HOSE NOZZLE.

Application filed November 1, 1927. Serial No. 230,293.

This invention relates to nozzles for filling gasoline into tanks of motor vehicles.

The object of this invention is to provide such a nozzle with a valve to close the passage through the nozzle when it is desired to remove the same from the tank.

The principal features of my invention consist in a spring pressed valve, guided by a valve stem which will seat itself when released, and stop the flow of gasoline therethrough.

These and other features of my invention are hereinafter described and are illustrated in the accompanying drawings, in which:

Figure 1 is a longitudinal central section of my improved nozzle.

Figure 2 is a side elevation of the valve stem of my improved nozzle, with the valve thereon in section, on an enlarged scale.

Figure 3 is a side elevation of the valve operating trigger of my improved nozzle showing the stuffing box thereon in longitudinal central section on an enlarged scale.

In these drawings A indicates the housing of my improved nozzle having an angular inlet stem A' adapted to be secured to a hose (not shown) leading from the usual pump mechanism (not shown).

B indicates a valve chamber, the rear end of which is closed by a closure plug B'. C indicates a passage from the valve chamber B to the nozzle D. C' indicates the chamber containing the valve operating lever C². Slidably mounted in guides E E depending from the wall a of the housing A, is a valve stem F on which is flexibly secured a valve F' see Fig. 2. The valve stem F is provided with a head f. Upon the stem F I place a sleeve f' which is provided with external threads adapted to engage the internal threads f² of the valve F'.

Between the head f of the valve stem F and the internal annular shoulder f² of the sleeve f' is a helical spring f⁴ which presses the head f of the valve stem F against the inner wall of the valve F'. Against the flange of the valve F' is a disk G of resilient valve packing which is held in place by a washer G', said washer G' being pressed against the packing disk G by the head of the sleeve f'. The opening through the sleeve f' is of a greater diameter than the valve stem so that said stem can assume an angular position therein as indicated by broken lines in Fig. 2. By means of this flexible construction the valve is free to adjust itself

to the valve seat. Within the chamber C' at the end of the passage C, is a valve operating lever C², which is mounted upon a pivot c in the upper part of the chamber C', said lever C² extending downward across the end of the valve stem, the free end of said lever C² being engaged by a roller H in the slidable trigger H', see Fig. 3. The slidable trigger H' passes rearward from the chamber C' through a packing box secured in the rear wall of the chamber C' in which J indicates the body which is screwed into the rear wall C³. The body member J is provided with packing J' through which the trigger H' passes. Upon the trigger H' I place a gland sleeve J² and I provide a cap J³ with internal threads adapted to be screwed over the threads j to press the gland sleeve J² against the packing J'. The roller H is mounted in a slot, (not shown) and the end of the lever C² extends through said slot and engages said roller so that when the hook h of said trigger H' is pulled backward the lever C² is caused to swing against the end of the valve stem which causes the valve F' to move away from the valve seat so that the spring K is compressed, and when the hook h is released the spring K closes the valve F' and the lever C² is moved by the valve stem to force the trigger H' back to its standing point. While the valve F' is raised off of the valve seat fluid is free to flow through the housing and nozzle D. The ends of the pivot c are soldered so that said pivot pin cannot be lost out, and gasoline or oil cannot leak out of the housing A. The nozzle tube D is provided with solder d which effectively seals the joint between said tube and the housing A.

Having thus fully described my invention so that the same can be utilized by others I do not desire to be limited to the exact construction shown and described as many modifications can be made therein without departing from the scope of my invention therefore what I claim as new and desire to secure by Letters Patent is:

1. In a device of the class described, a valve housing having a passage therethrough, an annular valve seat shoulder around said passage, valve stem guides extending transversely into said passage, a valve stem supported in said guides, a head on said valve stem, a valve having a screw threaded cavity to receive said head, a sleeve having its interior diameter greater than the diameter of said

valve stem and engaging the threads in said cavity whereby said valve is flexibly secured on said valve stem, and a spring between said valve and the closure cap of said passage.

2. In a device of the class described, a housing having a passage therethrough, an annular valve seat shoulder in said passage, valve stem guides extending transversely into said passage, a valve stem supported in said 10 guides on the center line of said passage, a head on said stem, a valve to close said valve

seat having a threaded cavity enclosing said head, a spring on said stem against said head, a threaded sleeve on said stem engaging the threads in said cavity and pressing said 15 spring against said head, and having an internal diameter greater than the diameter of said valve stem, so that said valve will be flexibly secured on said stem.

In testimony whereof I affix my signature.

ALMUS T. CARNES.
